UNITED STATES PATENT OFFICE.

FRANK HONIG, OF OAK PARK, ILLINOIS, ASSIGNOR TO CYCLO CORPORATION, OF CHICAGO, ILLINOIS, A CORPORATION OF ILLINOIS.

MECHANISM FOR AND METHOD OF COILING WIRE OR THE LIKE.

Application filed March 22, 1923. Serial No. 626,833.

This invention relates particularly to the forming of wire into coils by continuous action, or a non-stop operation.

The primary object is to provide a non-stop method of forming coils of wire, and improved mechanism for forming such coils, which will enable a continuous or non-stop method to be employed.

The invention may be applied to the re-winding of wire for various purposes; or, it may be applied to the drawing of wire. In the latter case, the improved mechanism may operate to draw the wire from the finishing die of a wire drawing machine, the wire drawing machine being provided with the usual drawing capstans and dies.

The invention is illustrated in the preferred embodiment in the accompanying drawing, in which—

Fig. 1 represents a broken vertical sectional view of the improved mechanism; Fig. 2, a horizontal sectional view taken as indicated at line 2—2 of Fig. 1; and Fig. 3, a broken elevational view of a detachable guard employed in connection with the cycloidal wire drawing mechanism.

In the construction illustrated, A represents a suitable frame; B, convolution-forming and discharging mechanism which operates to draw wire therethrough and discharge the same in convolutions about a suitable core; C, an intermittently actuated rotatable table equipped with a series of cores C'; and D, governing means serving to control the intermittent rotation of the table C.

The frame A may be of any suitable construction. In the form illustrated, the mechanism may be regarded as the take-up or wire coiling mechanism of a wire drawing machine of any approved form. A' represents a portion of the main frame which serves to support the convolution-forming and discharging mechanism B.

The mechanism B comprises, in the form shown, a tubular shaft 1 which is equipped with a bevel gear 1^a actuated by means of a bevel gear 2 on shaft 3; an arm or spider 4 fixedly secured to the lower end of or forming a part of the shaft 1 and rotating therewith; a planetary winding drum 5 secured to the lower end of a shaft 5^a which is journaled in the spider 4; a pinion 5^b secured to the upper end of the shaft 5^a and meshing with an internally toothed gear 6,

which is fixedly mounted on the frame member A'; a detachable drum or guard 7 carried by the spider 4; and a guide roller 8 mounted on the spider 4 and serving to guide the wire 9 to the planetary winding drum 5. The wire 9 passes through the hollow shaft 1, and may be drawn through a finishing die 10 which may be regarded as the finishing die of any suitable wire drawing machine. The wire 9 passes from the guide roller 8, and makes several turns about the planetary winding drum 5. The convolutions on the winding drum 5 are caused to grip the drum by means of a presser roller or gripping device 11. The wire passes from the drum 5 through a perforation 12 to the exterior of the drum. Convolutions 9^a are formed by the mechanism B, and these are deposited upon a core C' until a coil of suitable size has been formed. The table C is then rotated to remove the loaded core from the sphere of operations of the mechanism B and bring a fresh core in the position to be loaded.

The shaft 3 is further equipped with a bevel gear 13 which meshes with a companion gear at the upper end of shaft 14. The lower end of the shaft 14 has journaled thereon a gear 15 which is equipped with a clutch member 15^a. The shaft 14 has splined thereon a clutch member 16 which is automatically shifted periodically by means of a fork 17 which is pivotally supported at 18. The fork 17 is actuated by a vertical rod 19 which is pivotally connected with the member 17 at the point 19^a. The rod 19 has an extension at its lower end which is equipped with a tooth or dog 20, which normally engages the gear 15 and locks the same. Rod 19 is normally held in the position shown in Fig. 2 by a spring 21. The upper end of the rod is formed to provide a cam 19^b. This cam is adapted to be engaged by a cam 22 mounted on a ratchet wheel 22^a. At each revolution of the ratchet wheel, the rod 19 is depressed, thereby unlocking the gear 15 and throwing the clutch member 16 into engagement with the clutch member 15^a. The ratchet wheel is turned by means of a bell-crank actuating member 23, which is supported pivotally at 23^a. The member 23 has one end provided with a pawl 23^b. The other arm is provided with a cam stud 23^c which works in a cam groove of a cam 24 secured on the shaft 3. The

100 member 23 has one end provided with a pawl 23^b. The other arm is provided with a cam stud 23^c which works in a cam groove 105 of a cam 24 secured on the shaft 3. The 110

pawl 23^b oscillates through a given arc at each rotation of the shaft 3. However, the actuation of the ratchet wheel is regulated by means of an adjustable arm 25 secured to the pivot 23^a. The arm 25 carries at its outer end a cam 25^a which overlies the teeth of the ratchet. The pawl 23^b is adapted to ride on the cam 25^a a greater or less distance at each stroke, depending upon the adjustment of the cam 25^a. During the remaining portion of the forward stroke, the pawl turns the ratchet wheel. Thus, the mechanism D is adapted to regulate the period between actuations of the core-carrier C.

15 The core-carrier C is mounted on a central pivot 26, journaled in the frame A. The member C may be regarded as a circular table, which may be provided with any suitable number of cores C'. Each core C' has its lower end resting on the table and equipped with a spider 27 from which depends a stud 28. This stud may turn within the bearing 29 with a desired amount of friction, if desired; or, the core may be rigidly secured to a table. Where the convolutions 9^a are to be loosely deposited upon the core, the core will not turn on its own axis. Should the mechanism be so designed as to form small convolutions which will grip the core, as where it is desired to wind the wire tightly on the core, the core may be permitted to turn, under friction, about its axis. However, the present type of machine is primarily designed for use in situations where it is desired to have the wire formed into suitable coils which can be freely removed from the cores. The coils may be severed from each other, if desired, or they may be left connected to enable the wire to be put through any desired treatment or process.

40 In the operation of the improved machine, the spider 4 is rotated and the planetary winding drum is carried in an annular path and at the same time is rotated on its own axis. Thus, wire is continuously drawn on to the drum 5 and discharged therefrom; and as the wire is discharged from the planetary winding drum, it is formed into convolutions which are deposited upon the core.

45 The table C is provided with a large gear 28^a which meshes with the gear 15. The mechanism is so timed that when the desired number of convolutions have been deposited upon a core, the governing device D will operate to cause the gear 15 to be actuated, thereby turning the table through the necessary angle to bring a fresh core beneath the convolution-forming and discharging mechanism B. The drum or guard 7 is provided with slots 7^a of the type which engage lateral studs 7^b with which the spider 4 is equipped. The construction provides for raising the guard up out of the way, when it

is desired to have access to the winding drum. The invention affords take-up mechanism, or wire coiling mechanism adapted to a continuous wire drawing process. It also affords means for winding or re-winding wire or other flexible member by a continuous or non-stop process. The invention may therefore be adapted to numerous purposes.

10 The present invention constitutes a modification of the invention described in my pending application No. 693,264, filed February 16, 1924.

15 The foregoing detailed description has been given for clearness of understanding only, and no unnecessary limitations should be understood therefrom, but the appended claims should be construed as broadly as permissible.

20 What I regard as new and desire to secure by Letters Patent, is:

1. In combination, convolution-forming and discharging mechanism, a movable carrier equipped with a series of cores adapted to be placed, seriatim in position to receive the discharged convolutions, and means timed with said mechanism for periodically actuating said carrier, said last-named means being provided with means for varying the period between actuations of the carrier.

2. In combination, convolution-forming and discharging mechanism, including gripping means whereby a flexible member may be drawn through said mechanism, a plurality of shiftable cores, and means timed with said mechanism for periodically bringing a fresh core in position to receive convolutions and removing the filled core from the loading position.

3. In combination, convolution-forming and discharging mechanism provided with gripping means, a rotary table equipped with a plurality of cores, and mechanism timed with said first-named mechanism for periodically actuating said table while convolutions are being discharged.

4. In combination, planetary convolution-forming and discharging mechanism provided with gripping means, a rotary table equipped with a plurality of cores, and mechanism for periodically actuating said table, said mechanism being provided with means for varying the period between actuations.

5. The method of forming coils of wire which comprises carrying wire in an annular path and forming convolutions which are deposited about a shiftable core, and periodically shifting the loaded core and bringing into position a fresh core without severing the wire.

6. In combination, mechanism for forming and discharging convolutions, including a capstan upon which the strand is wound

and from which it is discharged, and an associated pressure device for causing the convolutions on the capstan to grip the capstan, a plurality of cores for receiving coils from said mechanism, and means from said mechanism, and means timed with said mechanism for periodically effecting shifting of the cores with relation to said mechanism during the discharge of convolutions from said mechanism.

5

7. In combination, mechanism for form-

ing and discharging convolutions, including a planetary capstan and an associated pressure device, a plurality of cores for receiving coils from said mechanism, and means timed with said mechanism for periodically 15 effecting shifting of the cores with relation to said mechanism during the discharge of convolutions from said mechanism.

FRANK HONIG.
